UNITED STATES PATENT OFFICE.

NICHOLAS P. PERKINS, OF CHARLESTON, WEST VIRGINIA, ASSIGNOR OF ONE-HALF TO
WILLIAM ADDISON CANTRELL, OF CHARLESTON, WEST VIRGINIA.

SCROLL-FORMING MACHINE.

1,249,474.

Specification of Letters Patent. Patented Dec. 11, 1917.

Application filed March 27, 1916. Serial No. 86,967.

To all whom it may concern:

Be it known that I, NICHOLAS P. PERKINS, a citizen of the United States, residing at Charleston, in the county of Kanawha and 5 State of West Virginia, have invented new and useful Improvements in Scroll-Forming Machines, of which the following is a specification.

This invention relates to shaping machines of general application, capable of 10 imparting a spiral-like configuration to a blank, and it is especially adaptive to the formation of scroll-like ornamentations on the necks of violins and other similar musical instruments.

One of the objects of this invention is to materially decrease the time, labor and expense incident to the production of scroll-like ornamentations on the necks of violins 20 and the like by accomplishing mechanically an operation heretofore manually performed.

A further object of this invention is to construct a machine characterized by simplicity and efficiency in operation, through 25 the instrumentality of which scroll-like ornamentations may be expeditiously, accurately and uniformly effected without employment of skilled labor.

30 A further object of this invention is to design a machine wherein, after the blank has been operatively positioned upon its support, rotation of the latter will automatically recede the blank with respect to the cutter, to effect the desired ornamentation.

With these and other objects in view, my 35 invention consists in certain novel details of construction, combination and arrangement of parts to be more particularly hereinafter set forth and claimed.

Briefly stated, this invention comprises 40 a horizontally disposed rotary spindle equipped with an angularly shaped cutter 45 adapted to operate upon a blank fixedly seated in a work-support situated in a plane oblique to the axis of the cutter, said support having, through suitably arranged operating mechanism, a spiraling movement, 50 whereupon, when actuated, it will cause the cutter to produce a spiral-like volute on the blank.

Referring more particularly to the draw-

ings, in which corresponding parts are indicated by similar reference characters:— 55

Figure 1 is a fragmentary side elevation, with parts shown in section, of my improved shaping machine, illustrating a neck operatively positioned and the scroll-like ornamentation partially formed. 60

Fig. 2 is a top plan view.

Fig. 3 is a fragmentary side elevation illustrating a neck operatively positioned with respect to the cutter.

Fig. 4 is a fragmentary perspective view 65 of the work-support mounting.

Fig. 5 is a fragmentary bottom plan view of the work-support.

In the manufacture of musical instruments such as violins, it has been the practice to effect the scroll-like ornamentations of the neck entirely by hand, but this method, owing to the expense entailed by the employment of skilled labor as well as the time required to complete the carving is 70 undesirable and it is therefore to the end that these deficiencies may be eliminated and work of the character specified rapidly, accurately and uniformly accomplished, that I have designed the machine constituting the 75 subject matter of this invention.

In the illustrated embodiment characterizing my invention, there is shown a supporting frame 1, having horizontally spaced bearings 2 which revolvably accommodate an 80 arbor or spindle 3. This spindle has a tapering extension 4, the outer extremity of which is adapted to receive a suitable cutter 5. The character of cutter depends largely 85 on the nature of the work, but preferably its cutting surface is angular in outline, wherein it may have a compound cutting effect, that is to say, the several convolutions and vertical walls of the scroll are simultaneously carved. A pulley 6 is secured to the arbor 3 intermediate its bearings, to be connected with a driving belt 7. 90

To position the work-support in angular relation with respect to the longitudinal axis of the cutter, a mounting 8 is employed comprising a casting 9, having therein a central opening 10, for a purpose hereinafter to be stated. One extremity of casting 9 has integrally formed therewith a clevis 11, the arms of which are adapted to embrace the 95 opposite sides of frame 1. The apertured 100

extremities of the clevis are pivotally connected to the bolt 12, slidably positioned in the vertically disposed transverse slot 13 formed in the frame. This construction affords a 5 pivotal connection of the casting with the frame, and, at the same time, permits the former to be vertically adjusted when necessary. The free extremity of casting 9 has integrally formed therewith an upwardly 10 and outwardly projecting extension 14 terminating in a collar 15 intended to encircle the cutter in a plane oblique to its axis. Collar 15 circumscribes an upstanding flange 16 surrounding annular opening 17 15 centrally formed in the annular work-support 18, said collar being maintained in position by the laterally extending flange 19 formed around periphery of auxiliary collar 19', in threaded engagement with flange 16, 20 as clearly shown in Fig. 1 of the drawings. Mounting the work-support 18 in this manner enables the latter to be freely rotated about its axis in a plane at an angle to that of the spindle, as will be readily understood 25 without further discussion.

The outer periphery of work-support 18 is beveled and cogged as at 21. These cogs miter with the teeth of pinion 22, which is keyed on the upper end of an externally 30 threaded pintle 23. The threaded portion of pintle 23 extends through the internally threaded opening formed in nut 24, which latter is seated in opening 24' in extension 25 of the frame. This nut is substantially 35 elliptical in outline, to afford an arcuate movement to the pintle as it moves therethrough, wherein it is continually maintained in proper relation with respect to the work-support. The upper end of pintle 23 40 passes through opening 10 in casting 9, and is rotatably connected thereto by suitable fastening elements 26. By virtue of this arrangement of elements, as work-support 18 is rotated, its movement will be imparted 45 to the pinion 22, and as this revolves, the pinion to which it is keyed will be caused to ascend or descend, dependent on the direction of rotation of the work-support. Meanwhile, since the casting 9 is connected with 50 the upper end of pintle 23, the ascension and descension of the latter will actuate said casting and its associated collar, to advance or recede the axis of the work-support with respect to that of the cutter.

55 The blank or neck 27 is secured to the under surface of work-support 18 by means of relatively arranged clamping members 28, with the portion to be operated upon seated in opening 17 of said work-support, wherein 60 it may be operated upon by the rotating cutter. In order to conveniently rotate the work-support, a hand-grip 29 is formed on the under surface thereof, adjacent its outer periphery, as shown in Figs. 1, 2 and 3 of 65 the drawings.

In operating the described machine to effect a scroll-like ornamentation on a violin neck, said neck has its shank engaged by clamping members 28 on the under surface of the work-support, with its knee seated in 70 the opening thereof in operative relation with respect to the cutter. After properly positioning the neck, the work-support is rotated, thus revolving the neck about the axis of its knee, said axis being, at the same 75 time, through mechanism hereinbefore described, gradually receded from that of the cutter, whereupon the latter, by virtue of this spiraling movement, will be caused to produce the spiral-like ornamentation shown 80 in Figs. 1 and 2 of the drawings. Although in the drawings and description, but one work-support is shown, it is understood that another could be conveniently affixed to the opposite side of the frame.

85 From the foregoing description it will be apparent that I have designed a scroll-forming machine of exceptionally few parts, as well as one which will enable the rapid production of an accurately and uniformly 90 carved scroll by inexperienced workmen.

Although in the foregoing, I have set forth certain elements as best adapted to perform the functions allotted to them, nevertheless, it is to be understood that various minor changes as to form, substance, etc., 95 may be resorted to, within the scope of the appended claims, without departing from or sacrificing any of the principles of this invention.

100 Having now described my invention, what I claim is:—

1. In a shaping machine of the character described, the combination of a rotary cutter and a coöperating spiraling work-support, 105 adapted to actuate the point of the work engaged by the cutter in a flat spiral course to produce a scroll-like ornamentation, substantially as and for the purpose set forth.

2. In a shaping machine of the character described, the combination of a rotary cutter and an angularly arranged spiraling work-support coöperating therewith, adapted to actuate the point of the work engaged by the cutter in a flat spiral course to produce a scroll-like ornamentation, substantially as and for the purpose set forth.

3. In a shaping machine of the character described, the combination of a horizontally disposed rotary cutter and a relatively arranged spiraling work-support coöperating therewith, and adapted to actuate the point of the work engaged by the cutter in a flat spiral course whereby to produce a scroll-like ornamentation, substantially as and for 120 the purpose set forth.

4. In a shaping machine of the character described, the combination of a horizontally disposed rotary cutter and an angularly arranged spiraling work-support coöperating 125

therewith, and adapted to actuate the point of the work engaged by the cutter in a flat spiral course whereby to produce a scroll-like ornamentation, substantially as and for the purpose set forth.

5. In a shaping machine of the character described, the combination of a rotary cutter, an annular work-support relatively arranged with respect to said cutter, and means 10 to impart a spiraling movement to the work-support, coincident with the plane of the latter to effect a scroll-like ornamentation on a blank, substantially as and for the purpose set forth.

15. 6. In a shaping machine of the character described, the combination of a rotary cutter, an annular work-support situated with its axis oblique to that of the cutter, and means to impart a spiraling movement to 20 said work-support coincident with the plane of the latter, to effect a scroll-like ornamentation on a blank, substantially as and for the purpose set forth.

7. In a shaping machine of the character described, the combination of a horizontally disposed rotary cutter, an annular work-support situated with its axis in angular relation with respect to that of the cutter, and means to impart a spiraling movement to 30 said work-support coincident with the plane of the latter to effect a scroll-like ornamentation on a blank, substantially as and for the purpose set forth.

8. In a shaping machine of the character described, the combination with a rotary spindle having an angularly faced cutter; of a spiraling work-support coöperating with said cutter, adapted to actuate the point of the work engaged by the cutter in 40 a flat spiral course to effect a scroll-like ornamentation, substantially as and for the purpose set forth.

9. In a shaping machine of the character described, the combination with a horizontally disposed rotary spindle having an angularly faced cutter, a spiraling work-support coöperating therewith, and situated with its axis in angular relation with respect to that of said cutter, said support being 45 adapted to actuate the point of the work engaged by the cutter in a flat spiral course to effect a scroll-like ornamentation, substantially as and for the purpose set forth.

10. In a shaping machine of the character described, the combination of a rotary cutter, an annular work-support coöperating with said cutter, and situated with its axis in angular relation with respect to that of the cutter, said support having therein a centrally arranged opening, means in connection with said support to seat a blank within said opening, and means to impart a spiraling movement to said support, whereby to 55 actuate the point of the blank engaged by the cutter in a flat spiral course to effect a 60

scroll-like ornamentation on said blank, substantially as and for the purpose set forth.

11. In a shaping machine of the character described, the combination of a horizontally disposed rotary cutter, a work-support co- 70 operating therewith and situated with its axis in angular relation with respect to that of the cutter, said support having therein a centrally arranged opening, means in connection with said support to centrally seat a blank within said opening, and means to impart a spiraling movement to 75 said support, whereby to actuate the point of the blank engaged by the cutter in a flat spiral course to effect a scroll-like ornamentation thereon, 80 substantially as and for the purpose set forth.

12. In a shaping machine of the character described, the combination of a rotary cutter, a vertically adjustable casting, a collar carried thereby and encircling the cutter in 85 a plane at an angle to the axis thereof, a work-support rotatably connected with said collar and means in connection with said adjustable casting and coöperating with said support, whereby, as the latter is rotated, 90 the point of the work engaged by the cutter will be actuated in a flat spiral course, substantially as and for the purpose set forth.

13. In a shaping machine of the character described, the combination of a rotary cutter, a vertically adjustable casting, a collar carried by said casting and encircling the cutter at an angle to its axis, a work-support rotatably carried by said collar, said support having therein a centrally arranged opening, a blank, means in connection with said support to centrally seat said blank in said opening, and means connected with said adjustable casting and coöperating with said work-support, whereby, as 100 the latter is rotated, said casting will be vertically adjusted to advance or recede the axis of said support with respect to that of said cutter, substantially as and for the purpose set forth. 105

14. In a shaping machine of the character described, the combination of a rotary cutter, a collar encircling said cutter at an angle to its axis, a casting carrying said collar, a vertically adjustable and arcuately movable pintle supporting said casting, a pinion keyed to said pintle, a work-support rotatably affixed to said collar, means on the periphery of said work-support to engage the teeth of said pinion to rotate the latter 115 and vertically actuate said pintle, whereby to advance or recede the casting of said support with respect to that of the cutter, substantially as and for the purpose set forth. 120

15. In a shaping machine of the character described, the combination of a horizontally disposed rotary spindle, a cutter carried thereby, a collar encircling said cutter at an angle to its axis, a vertically adjustable casting carrying said collar, a work-support ro- 125 130

5. rotatably carried by said collar, and means co-operating with said work-support and connected with said casting, whereby, as the former is revolved, the latter will be vertically adjusted to advance or recede the axis of the work-support with respect to that of the cutter, substantially as and for the purpose set forth.
10. 16. In a shaping machine of the character described, the combination of a horizontally disposed rotary cutter spindle, a collar encircling the cutter at an angle to its axis, a movable casting carrying said collar, a vertically adjustable and arcuately movable pintle connected with said casting, a pinion keyed to said pintle, an annular work-support rotatably affixed to said collar, said support having therein a centrally arranged opening, means in connection with said support to centrally seat a blank in the opening thereof to be operated upon by the cutter, and means on the periphery of said work-support co-acting with said pinion, substantially as and for the purpose set forth.
15. 17. In a shaping machine of the character described, the combination of a horizontally disposed rotary cutter spindle, a collar encircling the cutter, at an angle to its axis, a movable casting carrying said collar, a vertically adjustable pintle connected with said casting, means co-operating with said pintle to afford an arcuate movement of the latter, simultaneous with its vertical adjustment, a pinion keyed to said pintle, an annular work-support rotatably affixed to said collar, said support having therein a cen-

trally arranged opening, means in connection with said support to centrally seat a blank in the opening thereof, to be operated upon by the cutter, and means on the periphery of said support co-acting with said pinion, substantially as and for the purpose set forth.

40. 18. In a shaping machine of the character described, the combination of a frame, a rotary spindle positioned thereon, a cutter carried by said spindle, a collar encircling said cutter at an angle to its axis, a vertically movable casting carrying said collar, a work-support rotatably affixed to said collar, and having therein a centrally arranged opening, means in connection with said support to centrally position a blank in said opening, cogs on the periphery of said work-support, an extension on said frame, said extension having a seat therein, an elliptical shaped nut disposed within said seat and formed with an internally threaded opening, an externally threaded pintle co-operating with the opening in said nut, said pintle having its upper extremity connected with said casting and a pinion keyed to said pintle and mitering with the cogs on said work-support, whereby, as the latter is rotated, its axis will be advanced or receded with 55 respect to that of said spindle, substantially as and for the purpose set forth.

NICHOLAS P. PERKINS.
